(57) **CLAIM**

The ornamental design for a smart bird feeder, as shown and described.

DESCRIPTION

FIG. 1 is a front, left and top perspective view of a smart bird feeder, showing my new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of portion of FIG. 2 thereof.

The broken lines shown in the drawings illustrate portions of the smart bird feeder that form no part of the claimed design.

1 Claim, 9 Drawing Sheets
